UNITED STATES PATENT OFFICE

150,179

DESIGN FOR A CIGARETTE HUMIDOR
OR THE LIKE

Pauline B. Walters, Los Angeles, Calif.

Application July 21, 1947, Serial No. 140,433

Term of patent 14 years

(Cl. D85—2)

To all whom it may concern:

Be it known that I, Pauline B. Walters, a citizen of the United States, residing at Los Angeles, in the county of Los Angeles and State of California, have invented a new, original, and ornamental Design for a Cigarette Humidor or the like, of which the following is a specification, reference being had to the accompanying drawings, forming part thereof.

Figure 4 is a front perspective view thereof, as it appears in closed position, and

I claim:

The ornamental design for a cigarette humidor or the like, substantially as shown.

PAULINE B. WALTERS.
